UNITED STATES PATENT OFFICE

146,437

DESIGN FOR A BICYCLE FRAME

William Henry Taylor, Wednesbury, England,
assignor to The Birmingham Small Arms Company Limited, Birmingham, England, a British company

Application January 9, 1946, Serial No. 125,398
In Great Britain October 15, 1945

Term of patent 14 years

(Cl. D90—8)

To all whom it may concern:

Be it known that I, William Henry Taylor, a subject of the King of Great Britain, residing at 131 Hydes Road, Wednesbury, in the county of Stafford, England, have invented a new, original, and ornamental Design for a Bicycle Frame, of which the following is a specification, reference being had to the accompanying drawing, forming part thereof, and in which the figure is a perspective side view of a bicycle frame, showing my new design.

I claim:

The ornamental design for a bicycle frame, as shown.

WILLIAM HENRY TAYLOR.
